US00D603451S

(12) **United States Design Patent**
Gerules

(10) **Patent No.:** **US D603,451 S**
(45) **Date of Patent:** **** Nov. 3, 2009**

(54) **RETRACTABLE WRITING INSTRUMENT**

(76) Inventor: **Matthew J. Gerules**, 500 W. Superior St., Apt. 1410, Chicago, IL (US) 60610

(**) Term: **14 Years**

(21) Appl. No.: **29/322,850**

(22) Filed: **Aug. 13, 2008**

(51) **LOC (9) Cl.** **19-06**

(52) **U.S. Cl.** **D19/48**

(58) **Field of Classification Search** **D19/35, D19/36, 41, 42, 43, 44, 45, 46, 47, 48, 49, D19/50, 51, 54, 55, 56, 57; 24/11 F, 11 P, 24/11 R; 401/6, 52, 99, 100, 104, 105, 106, 401/107, 108, 109, 192, 195; 708/107**

See application file for complete search history.
